UNITED STATES PATENT OFFICE

171,837

SHEARS OR THE LIKE

Leonard Blanchaert, Milan, Italy, assignor to
Coltellerie Riunite di Caslino E. Maniago, a
limited corporation of Italy

Application August 22, 1952, Serial No. 21,166

Term of patent 7 years

(Cl. D22—5)

To all whom it may concern:

Be it known that I, Leonard Blanchaert, a citizen of Belgium, residing at Milan, Italy, have invented a new, original, and ornamental Design for a Shears or the like, of which the following is a specification, reference being had to the accompanying drawing, forming a part thereof.

Fig. 1 is a plan view of one side of a shears showing my new design;

Fig. 2 is a plan view of the side opposite that shown in Fig. 1 showing the shears in open position;

Fig. 3 is an edge view thereof taken from the right side of Fig. 1; and

Fig. 4 is an edge view of the opposite side thereof.

I claim:

The ornamental design for a shears or the like, as shown.

LEONARD BLANCHAERT.
